UNITED STATES PATENT OFFICE.

HERBERT O. HYATT, OF NEW YORK, N. Y.

DESIGN FOR A TOP FOR SHEET-METAL CANS.

No. 37,700.

Specification for Design.

Patented Nov. 28, 1905.

Application filed June 10, 1905. Serial No. 264,739. Term of patent 7 years.

To all whom it may concern:

Be it known that I, HERBERT O. HYATT, a citizen of the United States, and a resident of the city of New York, borough of Brooklyn, county of Kings, and State of New York, have invented a new, original, and ornamental Design for Sheet-Metal Cans, shown in the accompanying drawings, wherein—

Figure 1 is a plan view of the can, showing

the design invented by me. Fig. 2 is a side elevation of the same.

I claim—

The ornamental design for a sheet-metal can as shown.

HERBERT O. HYATT.
